(57) **CLAIM**

The ornamental design for sport pants, as shown and described.

DESCRIPTION

FIG. 1 is a front right top perspective view of a first embodiment of sport pants showing our new design;

FIG. 2 is a rear left top perspective view thereof;

FIG. 3 is a front elevational view thereof;

FIG. 4 is a rear elevational view thereof;

FIG. 5 is a top plan view thereof;

FIG. 6 is a right side elevational view thereof; and

FIG. 7 is a left side elevational view thereof.

FIG. 8 is a front elevational view thereof, wherein the pants are laid flat; and

FIG. 9 is a rear elevational view thereof.

FIG. 10 is a front right top perspective view of a second embodiment of sport pants showing our new design;

FIG. 11 is a rear left top perspective view thereof;

FIG. 12 is a front elevational view thereof;

FIG. 13 is a rear elevational view thereof;

FIG. 14 is a top plan view thereof;

FIG. 15 is a right side elevational view thereof; and

FIG. 16 is a left side elevational view thereof.

FIG. 17 is a front elevational view thereof, wherein the pants are laid flat; and,

FIG. 18 is a rear elevational view thereof.

Portions of FIGS. 1-18 that are shown as broken lines are for illustrative purposes only and form no part of the claimed design.
